Inventor
Thomas Graves,

By Richard B. Oliver,

Attorney

UNITED STATES PATENT OFFICE.

THOMAS GRAVES, OF MEMPHIS, TENNESSEE.

EGG TESTER.

Application filed October 7, 1921. Serial No. 506,049.

To all whom it may concern:

Be it known that I, THOMAS GRAVES, a citizen of the United States, residing at Memphis, in the county of Shelby and State 5 of Tennessee, have invented certain new and useful Improvements in Egg Testers, of which the following is a specification.

The present invention relates to egg testers and has for its principal object to generally 10 improve upon devices of this nature by providing a simple and efficient structure which will be durable and inexpensive, one which is efficient and reliable in operation and well adapted to the purpose for which it is de- 15 signed.

Another important object of the invention is to provide an egg tester capable of being readily opened so that easy access may be had to all parts thereof.

20 Another object of the invention is to provide an egg tester having an illumination compartment and a dark compartment with structure for supporting an egg therebetween so that it may be tested to advantage.

25 With the above and numerous other im- portant objects in view which will appear as the description progresses, this invention consists of certain novel features of construction, and the combination and arrange- 30 ment of parts as will be hereinafter more fully described and claimed.

In the drawing:—

Figure 1 is a perspective of the egg tester,

35 Figure 2 is a longitudinal vertical section therethrough,

Figure 3 is a transverse vertical section therethrough,

Figure 4 is a horizontal section through the lower compartment thereof showing the 40 same when batteries are used, and

Figure 5 is a similar view showing the same when the electric current is furnished from outside the egg tester.

Referring to the drawing in detail it will 45 be seen that 1 designates the base of the egg tester which has hingedly mounted thereon adjacent its longitudinal side edges the base side panels 2. Each side panel 2 is provided with end plates 3 at its transverse edge so 50 that when the panels are situated at right angles to the base 1 these plates 3 form end panels for the lower box-like structure. Hooks and eyes 4 are used for holding the plates 3 together. The opening 5 is formed 55 from notches in the plates 3 registering with

each other so that an electric wire as shown in Figure 5 may be passed therethrough and attached to an electric bulb 6 for the purpose of illumination. A switch 7 in one of the base side panels 2 is interposed between the source of electrical energy and the electric bulb 6. In Figure 4 it is shown that dry cells 8 may be used as a source of electrical energy if so desired and this latter form is preferable. The top plates 9 are fixed to the upper longitudinal edges of the panels 2 so as to extend at right angles thereto and form a top panel for the lower or illumination compartment which will preferably be painted white. Registered notches are also 60 provided in the top plates 9 so as to form an opening for supporting the egg 10 and this opening is preferably lined as indicated at 11. It is, of course, to be understood that as many of these openings may be provided 65 as may be found desirable. The upper or darkened compartment is formed by the upper side panels 12 and 13' which are hinged at 14' to the top plates 9. The upper side panel 12 is provided with the end panels 13 and cover panel 14. The cover panel 14 is held in engagement with the panel 13' by the hasp 15 which may be of any preferred construction. An opening 16 is pro- 70 vided in the cover panel 14 so as to be in registry with the egg receiving opening and a magnifying lens 17 is preferably placed 75 therein.

It is thought that the construction and operation of the egg tester will now be understood without a more extended explanation. As numerous changes in form, and in the combination and arrangement of parts may be made without departing from the spirit of this invention, I do not wish to be limited to the construction herein shown except 80 as hereinafter claimed.

Having thus described my invention what I claim as new is:—

1. An egg tester of the class described comprising an illuminated compartment includ- 100 ing a base panel, a pair of side panels, one side panel hinged to each longitudinal side edge of the base panel, four end plates one fixed perpendicularly at each end of each side panel so as to form end panels for the compartment, a pair of top plates one fixed perpendicularly to the free longitudi- 105 nal edge of each side panel to form a top panel, said top panel provided with an open- 110

ing; and a darkened compartment including side panels hinged to the top plates of the illuminated compartment, end panels fixed to one side panel of the darkened compartment and a hinged cover panel provided with an opening and engaged on one side panel of the darkened compartment.

2. An egg tester of the class described comprising an illuminated compartment including a base panel, a pair of side panels, one side panel hinged to each longitudinal side edge of the base panel, four end plates one fixed perpendicularly at each end of each side panel so as to form end panels for the compartment, means for holding adjacent end plates together, a pair of top plates, one fixed perpendicularly to the free longitudinal edge of each side panel to form a

top panel, adjacent edges of the top plate provided with registering notches to form an egg receiving opening; and a darkened compartment including side panels hinged to the top plate of the illuminated compartment, end panels fixed to one of the side panels of the darkened compartment, and a hinged cover panel on one side panel of the darkened compartment and provided with an opening registering with the egg receiving opening in the top panel of the illuminated compartment.

In testimony whereof I affix my signature in presence of two witnesses.

THOMAS GRAVES.
